LOUVER BOARD

Paul P. Heinley, Malibu, Calif.

Application June 23, 1952, Serial No. 20,315

Term of patent 14 years

(Cl. D21—6)

To all whom it may concern:

Be it known that I, Paul P. Heinley, a citizen of the United States, residing at Malibu, in the county of Los Angeles, State of California, have invented a new, original, and ornamental Design for a Louver Board, of which the following is a specification, reference being had to the accompanying drawing forming a part thereof.

Fig. 1 is a perspective view of a louver board, showing my new design; and

Fig. 2 is a cross-sectional view thereof, taken on line 2—2 in Fig. 1.

I claim:

The ornamental design for a louver board, as shown and described.

PAUL P. HEINLEY.
